LIGHTING FIXTURE ADAPTOR

Nathan R. Schwartz, Yonkers, N.Y., assignor to Swivelier Company, Inc., Nanuet, N.Y., a corporation of New York

Filed Mar. 3, 1965, Ser. No. 84,063

Term of patent 14 years

(Cl. D48—4)

FIG. 1.

FIG. 2.

FIG. 3.

FIG. 4.

I claim:

The ornamental design for a lighting fixture adaptor, as shown.
